United States Patent Office

Des. 185,372
Patented June 2, 1959

185,372

TABLE TOP OR SIMILAR ARTICLE

Bert J. Klein and Andre Bus, Altavista, Va., assignors to The Lane Company, Inc., Altavista, Va., a corporation of Virginia

Application March 23, 1959, Serial No. 55,120

Term of patent 14 years

(Cl. D33—14)

A table top or similar article embodying our new design is shown in a perspective view. Supporting legs for the table top or similar article are shown in dotted lines for illustrative purposes only.

We claim:

The ornamental design for a table top or similar article, substantially as shown and described.
